UNITED STATES PATENT OFFICE

RICHARD HOFSTADT, OF WOLFEN, AND WILHELM ELLER, OF DESSAU, GERMANY, AS-SIGNORS TO I. G. FARBENINDUSTRIE AKTIENGESELLSCHAFT, OF FRANKFORT-ON-THE-MAIN, GERMANY, A CORPORATION OF GERMANY

TREATMENT WITH LIQUID OF FIBERS WOUND UPON PERMEABLE SPOOLS

Application filed May 31, 1928, Serial No. 281,963, and in Germany July 25, 1927.

The present invention relates to an apparatus for treating artificial fibers with liquids and particularly to an apparatus in which artificial silk wound on permeable spools is treated with liquids by pressure or suction. Artificial silk wound on permeable spools has been washed or after-treated by forcing or sucking liquid through the spools, the ends of the latter being closed by covers fixed by 5 wing nuts (compare French Patents Nos. 527,720 and 547,834). In later apparatus it has been tried to simplify this troublesome arrangement. Thus Swiss Patent No. 115,282 provides stoppers for fitting tightly into the 10 spools. In another device, the spools are threaded upon a perforated tube, on which they are held tightly by conical intermediate pieces or bottom plates and covers between 15 which they are held by means of a wing nut. All these devices have the disadvantage 20 that mounting the spools (each of which may have to be handled separately) consumes costly labour and is a comparatively slow operation. Moreover, the apparatus required is expensive and the quality of the silk 25 is not improved. Devices having screwing arrangements have special disadvantages which are obvious.

The present invention greatly simplifies 30 the treatment of the silk on spools, by substituting mechanical mounting and dismounting of the spools to the exclusion of manual operation.

The invention will be explained with reference 35 to the accompanying drawings, in which:—

Fig. 1 is a perspective view of a cover plate for a number of spools or of an intermediate carrying plate;

Fig. 2 is a longitudinal section of Fig. 1;

Fig. 3 is a vertical section drawn to an enlarged scale through a portion of a cover plate, and Fig. 4 is a like section through portion of an intermediate plate;

Fig. 5 is a vertical section through a washing box packed with spools, and Fig. 6 is a like view of a modification of the box.

The cover or intermediate plate A, consisting 50 for example of iron covered with rubber, has a number of perforations B, B₁, B₂, cor-

responding with the number of spools to be accommodated and spaced at the required distance apart. These perforations are to receive with some play, particularly in the vertical direction, the intermediate pieces or 55 cover pieces which make a tight joint with or close, respectively, the ends of the spools. The plate is recessed at the edges and in some cases also perforated in the parts between the aforesaid perforation, in order that the washing liquids may have unhindered access to the spools; further the plate is shaped at its corners to form guides C (or mounting and dismounting) and has shoulders at D, D₁ to facilitate engagement with the grippers of a 60 crane crab to lift it horizontally out of the container. In this case these spools can remain on the plates and be put in another container for a further treatment; finally, distance pieces E are provided for protecting 65 the plate from those above and below it when several plates are piled one upon the other. The spools are to be carried between pairs of these plates, for which purpose the cover plate A carries in the perforations B, B₁, B₂ 70 cover pieces (see Figure 3) which are to close the upper ends of the top layer of spools, while the intermediate plates A₁ (Fig. 4) carry in the perforations intermediate pieces 75 (see Figure 4) which are perforated for passage of liquid and serve to close the lower ends of the spools above them and the upper ends of the spools below them. The kind, form and material of these inserted pieces 80 may obviously be widely varied, provided that the pieces have a certain vertical play for compensating any difference which there 85 may be between the heights of the spools and of the intermediate pieces.

In Fig. 3 F is a porcelain cover piece made 90 tight with the spool by means of a rubber ring G and prevented from falling through the perforation B by means of a rubber ring H which permits vertical play as indicated at K. When all the spools are in place the 95 plate A rests on the flange J of the cover. An analogous construction of an intermediate piece is shown in Fig. 4, the parts being F₁, G₁, H₁, J₁, K₁, respectively. A plate A₁ 100 is charged with spools, for instance by be-

- ing placed on the spools in a frame in which they are arranged in precisely the same manner as the perforations in the plate; the frame and the plate are then turned through 5 an angle of 180° and the frame removed. The plate thus charged is then lifted by a crane crab and lowered into the box L (Fig. 5). A second charged plate follows and so on, until there is thus formed a structure of 10 columns of spools which are stiffened by the carrying plates, the spools being tightly closed by their weight and by that of the cover A which is applied to the topmost layer, although further pressure may be applied by means of lever devices M. It will be understood that in the container L the false bottom need only be perforated correspondingly with the lowest carrying plate in order that it may receive the whole structure; 15 indeed, this false bottom may be omitted and there may be substituted, as shown in Fig. 6, an internal rib O with a tightening washer for supporting the lowest carrying plate, which should be correspondingly strength- 20 ened.
- What I claim is:—
1. In an apparatus for treating with liquids artificial fibers wound on permeable hollow spools, in operative combination, a 25 container, a plurality of removable intermediate horizontal plates therein spaced at a substantial distance from one another and provided with uniformly spaced perforations, annular members loosely carried in said 30 perforations and adapted to engage the adjacent ends of the spools immediately above and below said annular members, a removable cover plate provided with perforations corresponding to the perforations in said 35 intermediate plates, and cover members loosely carried in said perforations in the cover plate and adapted to close the upper ends of the 40 uppermost set of spools.
  2. In an apparatus for treating with liquids artificial fibers wound on permeable hollow spools, in operative combination, a 45 container, a plurality of removable intermediate horizontal plates therein spaced at a substantial distance from one another and 50 provided with uniformly spaced perforations and with means for engaging a lifting device, annular members loosely carried in said perforations and adapted to engage the adjacent ends of the spools immediately above 55 and below said annular members, a removable cover plate provided with perforations corresponding to the perforations in said intermediate plates, and cover members loosely 60 carried in said perforations in the cover plate and adapted to close the upper ends of the 65 uppermost set of spools.
  3. In an apparatus for treating with liquids artificial fibers wound on permeable hollow spools, in operative combination, a 70 container, a plurality of removable intermediate horizontal plates therein spaced at a substantial distance from one another and provided with uniformly spaced perforations, annular members loosely carried in said perforations and adapted to engage the adjacent ends of the spools immediately above and below said annular members, a removable cover plate provided with perforations corresponding to the perforations in said intermediate plates, and cover members loosely carried in said perforations in the cover plate and adapted to close the upper ends of the uppermost set of spools.

4. In an apparatus as set forth in claim 1, a false bottom spaced at a substantial distance from the bottom of the container and provided with perforations adapted to carry the same sort of annular members as the intermediate plates, permitting circulation of the treating liquid from the bottom of the container.

In testimony whereof, we affix our signatures.

RICHARD HOFSTADT.
WILHELM ELLER.
